(57) **CLAIM**

The ornamental design for a display screen or portion thereof with animated graphical user interface, as shown and described.

DESCRIPTION

This application is related to three (3) other co-pending U.S. applications, filed on even date herewith, and identified by the following titles: Ser. No. 29/716,847 entitled "Display Screen or Portion Thereof with Graphical User Interface"; Ser. No. 29/716,863 entitled "Display Screen or Portion Thereof with Icon"; and Ser. No. 29/716,868 entitled "Display Screen or Portion Thereof with Icon". Each of these co-pending U.S. applications are hereby incorporated by reference herein in their entirety.

The patent or application file contains at least one drawing executed in color. Copies of this patent or patent application publication with color drawing(s) will be provided by the Office upon request and payment of the necessary fee.

FIG. 1 is a first image of a display screen or portion thereof with animated graphical user interface showing our new design according to a first embodiment.

FIG. 2 is a second image thereof.

FIG. 3 is a third image thereof.

FIG. 4 is a fourth image thereof.

FIG. 5 is a first image of a display screen or portion thereof with animated graphical user interface showing our new design according to a second embodiment.

FIG. 6 is a second image thereof.

FIG. 7 is a third image thereof; and,

FIG. 8 is a fourth image thereof.

The appearance of the animated graphical user interface sequentially transitions from FIG. 1 to FIG. 4 in the first embodiment and from FIG. 5 to FIG. 8 in the second embodiment. The process or period in which one image transitions to another forms no part of the claimed design. The outermost, peripheral broken line shows a display screen, or portion thereof, in environment, and forms no part of the claimed design. The other broken lines within the
